208,913

SEPARABLE MAGNETIC HOLDER FOR SECURING FABRIC AND PATTERN

Anna M. Techtmann, 77 NE. 100 St.,
Miami Shores, Fla. 33153

Filed Aug. 22, 1966, Ser. No. 3,557

Term of patent 3½ years

(Cl. D26—1)

FIG. 1

FIG. 2

FIG. 3

FIG. 4

FIG. 1 is a front elevation of a separable magnetic holder for securing fabric and pattern, showing my new design.

FIG. 2 is a side elevation thereof.

FIG. 3 is a top plan view thereof.

FIG. 4 is a bottom plan view thereof.

I claim:

The ornamental design for a separable magnetic holder for securing fabric and pattern, as shown.
